G. HELGE

WINDOW LATCH AND DRAFT PLATE

Filed Oct. 5, 1926

INVENTOR
Gustav Helge

BY
Peter M. Boisnay
ATTORNEY

UNITED STATES PATENT OFFICE.

GUSTAV HELGE, OF BROOKLYN, NEW YORK, ASSIGNOR OF ONE HALF TO GEORGE W. NUNEMAN, OF BROOKLYN, NEW YORK.

WINDOW LATCH AND DRAFT PLATE.

Application filed October 5, 1926. Serial No. 139,628.

This invention relates to improvements in double-hung window sashes, and has for its object to provide a metal steering plate and window latch forming an integral combination, and operating in conjunction with the lower and upper sash, and which has for its object to remedy and eliminate several objectionable conditions inevitably found existing in the use of such windows aforementioned.

Such needs and purposes will hereinafter more fully be described and pointed out.

The bottom part, or metal steering plate, will thus eliminate all dust and draft from the corners of double hung windows at meeting rails, where sashes meet parting strip on sides of jambs, while the upper part, or latching member, will securely interengage such windows in any desired position.

With the further appliance of an independent device, not described, shown, or claimed, herein, as it may consist of a simple hook, or similar apparatus, fastened to the sash, and adapted to engage recesses or notches in the frame, this invention will practically render such windows burglar-proof, and the combined adjustment may be to the effect that no person will from outside be able to enter, or operate the combination-lock as thus described.

Said combination will furthermore on account of its special construction act as a steering guide for loose and rattling windows.

As a patent application has been filed by me, June 29, 1926, under Serial No. 119,294 for improvements in draft plates for windows, and as this invention constitutes a further improvement of such device, while at the same time forming an integral combination with the former, I shall in this application confine my description and claims to said improvements in window latch and draft plates.

In a slightly modified form the latching member of my device may be used instead of the ordinary window clasp, as I in this case use a special foot-plate as shown clearly in Fig. 6.

With the above and other objects in view,

this invention consists of the novel features of construction, combination and arrangements of parts, hereinafter fully described, claimed, and illustrated in the accompanying drawings forming parts of this specification, and in which similar characters of reference indicate corresponding parts in all views, and in which;

Figure 1 is a perspective view of my invention; Figs. 2 and 3 illustrate the construction of the combined latch mechanism; Fig. 4 is a top view of the combined device; Figs. 5 and 6 show my device in a modified form. Fig. 7 is a detail view of two latch members.

Referring more particularly to the drawings, 17 designates a fastening member formed integrally with the plate 10, the latter indicates a metal plate adapted to be fastened on top at one upper corner of the lower sash of a double hung window. Said plate is provided with a substantially square, cut out portion 11 to allow space for, and form a snug fitting with, the parting strip 15 of the window. This plate has a further reduced portion as shown at 12, providing sufficient space for the sash cord 16, for which purpose it has at its base, been formed with a slight, inward curvature 13. This reduced portion further takes in space, as indicated at 14, in order to permit the passing of the sash pulley, when the sash is opened and raised to the top of a window frame.

The said fastening member 17 comprises a frame 18, side walls 19 and a lever or handle 20. To said lever is pivotally engaged, in the manner shown, a stop-member 21, and a release member 22. Said lever is turnably seated on an axle 23, the latter being rigidly supported by the walls 19. It will be noticed that the members 21 and 22 have a reenforced bearing 24 at the section where the engagement with the lever takes place. Said lever connects with members 21 and 22 by means of bifurcated sections 25 formed on the latter and pivotally connected by means of axle pins 26.

The action of the fastening-mechanism is accentuated and controlled by two springs

27 and 28, preferably made from springy wires and both of which are wound around a block-rod 29.

While these springs have the movements of their shorter end pieces arrested by the wall or bottom of the frame-casing, their longer endpieces exert a pressure, that of 27 on the lever, and that of 28 on the bottom part of the release member. To secure a steady movement of said springs the lever and release-member are respectively provided with a slight trough, or recessed section, as shown at 30 and 31, adapted to hold and steady the movement of said springs during the manipulation of the latch members.

The frame wall 32 has two cut out, substantially rectangular, portions 33 and 34 in order to permit of the movement during manipulation of the members 21 and 22; in this respect it will be noticed that the opening 34 does not in shut position of the fastener make a very compact fitting with the release member 22, but has a little superfluous space 35 in order to permit of a somewhat freer upward movement of the said member when this goes into a cocked position by means of engaging a notch 36 on same with the upper edge of said opening 34.

The structure and walls of the latch-mechanism may be secured together by means of rivets or small metal bolts 38.

In raising and adjusting the windows when in shut position the lever 20 which moves in an oblong slot 41 is pulled back, incidentally disengaging and retracting the member 21 causing a release, while simultaneously the member 22 is thrust forward.

By raising the sash to a desired height the said member 22 will upon meeting a stopper 37, a small, preferably metal, strip, of which there are several attached to the other window section, be pushed back where by a reverse movement of the lever and member 21 takes place causing the window sections to be adjusted in a secure position.

When I employ my device solely as a fastening member, I preferably attach such fastener to the middle part of a window sash, while for the purpose of securing said window sections together rigidly attach to the other window section a member or hook 39, as shown clearly in Fig. 5. In this case the foot-plate of the fastening member would have a slightly modified form 40, as shown in Fig. 6. Said fastening device will naturally operate automatically in shutting the windows. It is obvious that changes may be made in the form, construction and arrangement of the several parts as shown, within the scope of the appended claims, without departing from the spirit of the invention, and I do not therefore limit myself to the construction and arrangement shown and described herein.

What I claim as new, and desire to secure by Letters Patent of the United States, is:

1. A combined window-latch and draft-plate for double-hung windows comprising an erect, narrow casing with a beveled roof, said casing embracing a control-lever engaged by contact members, and actuating means, the said casing being integrally mounted on a flat, substantially rectangular draft-plate, the latter having the edge of one side indented, as and for the purpose described.

2. A combined window-latch and draft-plate for double-hung windows having a substantially rectangular bottom plate, a casing rigidly attached thereto and working in conjunction therewith, said casing comprising two side plates, the closure being completed by a vertical edge-plate, and an elongated beveled roof-plate, the former being provided with two substantially rectangular openings to permit free movements of a stop and release member, the latter having an oblong slit for operation of the control lever; said lever being mounted on an axis supported in the side-walls, a stop and release member pivotally engaged to said lever by means of bifurcated sections and adapted to perform reciprocating movements, two springs held by a rod and engaging respectively the lever and the release member, troughs in said lever and release member serving as guides for said springs and to secure a steady movement, the stop and release member adapted alternately to engage and release said mechanism in relation to projections mounted on the other corresponding window-section.

3. A device as described, comprising a flat-sided, erect casing, a control-lever turnably mounted on a pin rigidly supported by the side walls of said casing, a stop and release member, each having one end terminated in a bifurcated section and pivotally connected to said lever, two actuating springs, held by one rod and working in conjunction with the control-lever and the release member respectively, troughs in said lever and latter member adapted to serve as guides for those, a recess provided in the upper edge of the release member for engagement with the vertical flange of the casing when said member goes into cocked position and the mechanism is disengaged substantially as shown and described.

4. In an automatic latch device, as described working in conjunction and forming an integrity with a window-dust plate, a lever mounted on a central axle, said axle being supported by the side walls of the casing, a stop and release member provided each with bifurcated sections and having

said sections pivotally connected to the lever, springs actuating the movements of said lever and release member, the latter being provided with an upper recess adapted to engage the upper edge of a cut-out portion of the vertical edge-plate of the casing, said cut out portion being of a substantially greater dimension than said release member in order to permit of a free

movement of the latter when it goes into a 10
cocked position; while the stop member is
adapted to engage automatically a counter-
part on the other window section in shut-
ting the windows, substantially as shown and
described.

In testimony whereof I have hereunto af-
fixed my name.

GUSTAV HELGE.
